UNITED STATES PATENT OFFICE.

ANDREW MORRISON, OF PENN TOWNSHIP, ALLEGHENY COUNTY, PENNSYLVANIA,
ASSIGNOR TO DILWORTH, PORTER & COMPANY, INC., OF PITTSBURGH, PENNSYLVANIA, A CORPORATION OF PENNSYLVANIA.

TIE-PLATE.

1,357,179.

Specification of Letters Patent. Patented Oct. 26, 1920.

Application filed August 2, 1920. Serial No. 400,687.

To all whom it may concern:

Be it known that I, ANDREW MORRISON, a citizen of the United States, residing at Penn township, in the county of Allegheny and State of Pennsylvania, have invented 5 a new and useful Improvement in Tie-Plates, of which the following is a full, clear, and exact description, reference being had to the accompanying drawings, forming 10 part of this specification.

The present invention relates broadly to railways and more particularly to tie plates for use in road construction.

The principal object of the present invention 15 is to provide a tie plate which may be easily produced by rolling and which will embed itself in the fibers of the tie to prevent lateral movement of the rails without producing any objectionable cutting action 20 on such fibers.

A further object of the present invention is to provide a tie plate having a series of 25 projections on the lower face thereof, which result in a gradual change of cross sectional area of the tie plate and which are so proportioned that their different dimensions bear predetermined definite relations to each other.

The foregoing and other objects, together 30 with their attendant advantages, will be apparent as the invention becomes better understood, by reference to the accompanying specification and drawings forming a part thereof, it being premised that changes may 35 be made in the various details and the manner of operation, within the scope of the appended claims, without departing from the spirit of the invention.

Figure 1 is a sectional view through one 40 form of tie plate constructed in accordance with the present invention;

Fig. 2 is a similar view of a slightly modified form of tie plate;

Fig. 3 is a plan view of a tie plate having 45 a portion of a rail in position thereon; and

Fig. 4 is a diagrammatic view.

Referring more particularly to the drawings there is illustrated a portion of a tie 2 having in operative position thereon a tie 50 plate 3 which is tapered throughout the major portion of its length to provide a construction somewhat similar to that disclosed in the patent to Clark No. 529,854 of November 27th, 1894. With this type of construc-

tion, the resultant wheel load produced by 55 the wheel load and the wheel thrust, as clearly indicated by the arrows in Fig. 4, is counteracted by the relatively thicker portions of the tie plate whereby breaking thereof is prevented. 60

The tie plate is preferably provided with the usual rail abutment or shoulder 4 and with the spike openings 5.

In order to prevent lateral movement or 65 spreading of the rails, it is necessary to provide the tie engaging surface of the tie plate with a series of projections adapted to embed themselves in the tie fibers. By experiment I have found that projections having a base width from the center line of each 70 of the projections, as clearly shown in Fig. 4, to the termination of the inclined portion on at least one side of the center line, greater than twice the depth of the projections at the highest point but less than the distance 75 between the highest points of adjacent projections, is highly desirable and efficient.

In Fig. 1 the tie plate 3 is illustrated as provided with three projections 6, each extending transversely and continuously 80 throughout the entire width of the tie plate. One of the projections 6 is so positioned that the center line thereof lies directly under the line of junction of the rail abutment 4 with the main body of the tie plate 3. The 85 other projections are so positioned that the center lines thereof will coincide respectively with the center line of a rail 7 placed thereon, and with the opposite edge of the rail.

This particular construction is highly 90 desirable in that reinforcements are provided at the points of greatest strain. The abrupt change in section produced by forming the rail abutment 4, produces a weak 95 point at the line of junction between the abutment and the body of the tie plate, which point is reinforced by the projection 6 located immediately therebeneath with the greatest body of metal effectively positioned to prevent the plate from cracking.

Referring more particularly to Fig. 4, it will be apparent that the base width of each of the projections from the center line to the termination of the inclined portion thereof, is greater than twice the depth of 105 the projection. Due to this construction the angle of inclination is comparatively slight and the projections embed themselves

without exerting any cutting action on the tie fibers. In addition, they may be effectively formed on the plate without producing any abrupt change in section such as produced by the teeth or spurs of the Clark patent before referred to. This construction is important in that in rolling a tie plate each abrupt change in section produces the equivalent of an initial fissure in the plate.

10 Inasmuch as the projections extend continuously throughout the width of the plate, there is exerted a maximum resistance against lateral movement.

With the construction disclosed in Fig. 2, the projections 6' each has one of its sides 7 gradually inclined from the center line as before described, while the opposite side 8 of each of the projections extends more abruptly from the center line to produce 20 an abutment or shoulder presented to the tie fibers. It is essential with such a construction that the high point of the projection be rounded to form a non-cutting edge and that the shoulder be joined to the 25 main body of the plate by a gradually curved body of material to prevent the formation of abrupt changes of area.

With both of the forms of invention described, it will be apparent that the projections alternate with intermediate flat bearing surfaces 9, which limit the extent to which the projections may embed themselves in the tie, and form large areas of contact with the tie surface, thereby firmly 35 supporting the rails in position.

The advantages of the present invention arise from the construction of the tie plate with the projections proportioned and positioned to exert a maximum reinforcing action and effectively prevent lateral movement of the tie plates.

I claim:

1. A tie plate having a lower tie engaging surface provided with a series of projections extending continuously through the major portion of the width of the plate, and each having a base width greater than twice the depth thereof but less than the distance

between the greatest depths of adjacent projections, substantially as described.

2. A tie plate having a lower tie engaging surface provided with a series of projections extending continuously across the major portion of the width of the plate, and each having a base width from the center line thereof to the termination of the inclined portion greater than twice the depth of the projection but less than the distance between the center lines of adjacent projections to provide flat bearing surfaces therebetween, said projections being positioned to directly underlie the edges and center line of the rail supported by the tie plate, substantially as described.

3. A tapered tie plate having a lower tie engaging surface provided with a series of projections extending continuously across the major portion of the width of the plate, and each having a base width from the center line thereof to the termination of the inclined portion greater than twice the depth of the projection but less than the distance between the center lines of adjacent projections to provide flat bearing surfaces therebetween, said projections being positioned to directly underlie the edges and center line of the rail supported by the tie plate, substantially as described.

4. A tapered tie plate having a lower tie engaging surface provided with a series of projections extending continuously across the major portion of the width of the plate, and each having a base width from the center line thereof to the termination of the inclined portion on one side of the center line greater than twice the depth of the projection but less than the distance between the center lines of adjacent projections to provide flat bearing surfaces therebetween, said projections being positioned to directly underlie the edges and center line of the rail supported by the tie plate, substantially as described.

In testimony whereof I have hereunto set my hand.

ANDREW MORRISON.
